VENTILATOR

Adolph T. M. Biancani, Elko, Nev.

Application July 19, 1946, Serial No. 684,636

7 Claims. (Cl. 98—116)

1

This invention relates generally to ventilators of the type adapted to be installed in a wall for moving air into or out of a room or building space.

It is an object of the invention to provide a ventilator of the above type having improved means for closing the passage through the same, when the device is not in use. This means operates entirely automatically, and serves to positively lock the closure means in closed position.

It is a further object of the invention to provide an improved ventilator of the above type which can be used for movement of air in either direction, that is, either from the exterior into the room, or from the room to the exterior.

A further object of the invention is to provide an improved ventilator having automatically operated closure means for the passage through the housing, characterized in particular by the fact that the operating parts of the same are relatively simple in construction, positive in operation, and will function for long periods of time without frequent servicing or repairs.

An additional object of the invention is to provide an improved centrifugal operator for a ventilator of the above character.

Another object of the invention is to provide improved means for locking the closures in closed position, and to provide improved means for effecting automatic unlocking of the same.

Further objects of the invention will appear from the following description in which the preferred embodiments are set forth in detail in conjunction with the accompanying drawing.

Referring to the drawing:

Figure 1 is a side elevational view of a ventilator incorporating the present invention.

Figure 2 is a view of the ventilator shown in Figure 1 but looking toward the front end of the same, with certain of the parts illustrated in section.

Figure 3 is a plan detail showing the spring means for urging the doors toward both closed and open positions.

Figure 4 is a sectional view taken along the line 4—4 of Figure 1, but with the propeller and the means for supporting the electric motor being removed for clarity.

Figure 5 is a sectional view like Figure 4 but showing the closure doors in full open position.

Figure 6 is a sectional view taken along the line 6—6 of Figure 4.

Figure 7 is a sectional detail on an enlarged scale taken along the line 7—7 of Figure 4.

2

Figure 8 is a sectional detail showing a part of the operating connection between the centrifugal operator and the closure doors.

The embodiment of the invention illustrated in the drawing consists generally of a housing 10 which can be formed of suitable sheet metal, and which for convenience is cylindrical shaped and is adapted to be inserted in a wall 11 (Figure 4). Disposed axially within the housing there is a shaft 12 which can be extended from or directly coupled to the shaft of an electric driving motor 13. Suitable means such as the supporting arms 14 serve to carry the motor upon the housing.

15 Mounted upon the exterior face of the housing 10 are the closure doors 16. The inner adjacent edges of these doors are attached to the shafts 17, which extend diametrically across the housing, and which have their ends pivoted or 20 journaled within the pads or bosses 18, 19. The upper ends of the shafts 17 are provided with cranks 21, which in turn are connected together by the tension spring 22. When the doors 16 are closed the spring occupies a position relative to the cranks 21 substantially as illustrated in Figure 3. However when the doors are swung to full open position (Figure 5) the cranks 21 pass through dead center position with respect to the pull of the spring. Thus the spring tends 25 to urge the doors toward full closed and full open positions, from an intermediate dead center position. It is desirable to have the cranks 21 together with spring 22 enclosed within the protecting cap 23. The peripheral edge portions of 30 the doors seat upon a sealing gasket 25 which can be made of resilient material such as rubber. Beyond the doors the housing can be provided 35 with a hood 10a.

The shaft of the motor is provided with a hub 40 24, to which the fan or impeller blades 26 are attached. These blades may be made to enable rotation in either direction, and are proportioned to operate within the housing 10. For simplicity they are illustrated diagrammatically by dotted 45 lines in Figures 4 and 5.

A novel type of centrifugal operator 28 is mounted upon the shaft 12 adjacent the fan. This operator consists of a plurality of arcuate or curved members 29, which have considerable 50 weight, including if necessary the weighting 31 on their outer free ends. The inner ends of members 29 have pivotal connections 32 with the ears 33. These ears are fixed to a hub 34, which together with the hub 24 of the impeller, 55 is fixed to the shaft.

A collar 36 is slidably carried by the shaft 12, and certain parts connect this collar to the doors 16 and to the latching means to be presently described. Acting between the collar 36 and the members 29 there is a thrust transmitting device 37. Collar 36 carries an oil sealed bearing assembly, the inner sleeve of which is attached to device 37 and slidably longitudinally upon the shaft 12. A plurality of tension springs 38 connect between the device 37, and the hub 24 of the impeller. Members 41 extend radially from the device 37 and provide spaced ears 42, between which the members 29 are accommodated. Rollers 43 are mounted between the ears 42 and receive thrust from the member 29. The journaling of device 37 relative to the hub 36 is such that when forces are applied to device 37 to move the same longitudinally of the shaft, such movement is transmitted to the collar 36. When shaft 12 is rotated at a proper speed corresponding to a minimum normal speed of operation, members 29 swing outwardly by centrifugal force, thus transmitting longitudinal movement to device 37 and collar 36 against the urge of springs 38. When the shaft is permitted to come to rest members 29 swing inwardly and the parts return to their initial positions shown in Figure 4.

Means are provided for connecting the collar 36 with the door 16 to effect opening and closing movements of the same. The means illustrated consists of arms 44 mounted upon collar 36 and extending radially from the same, and which have pivotal connections 46 with the extensible links designated generally at 47. These links in turn have pivotal connections 48 with the doors 16, the connections being located on opposite sides of shafts 17 (Figures 4 and 5).

The extensible links 47 can be formed substantially as illustrated in Figure 8. Briefly they consist of inner and outer telescoping members 47a, 47b, together with a compression spring 51 serving to urge these members apart. Member 47a is shown provided with a flattened side 52, serving to accommodate the stop pin 53. Thus movement of members 47a, 47b toward each other is limited by engagement of shoulder 54 with the pin 53. Likewise the shoulder 56 strikes a pin 53 to limit movement of members 47a, 47b apart. When collar 36 is moved by the centrifugal device 28 toward the doors 16, thrust is transmitted through the links 47 (with pin 53 and shoulder 54 in contact) to rotate the doors past dead center position with respect to spring 22. Thereafter the doors move quickly under the urge of spring 22 to the full open positions shown in Figure 5, and to accommodate such movements parts 47a, 47b extend to bring pin 53 in engagement with shoulder 56. When driving of the shaft is discontinued and collar 36 caused to move back to the position illustrated in Figure 4, the doors are pulled toward closed position past dead center position, and thereafter the doors quickly move under the urge of spring 22 to full closed position.

In conjunction with the parts described above I provide latching means which engages automatically, and which is automatically released by forces from the centrifugal device 28. Thus I provide extensible links 58 which have their inner ends pivotally connected at 59 to the arms 44 of the hub 36, and which have their outer ends provided with pivotal connections 59 to the side walls of the housing 10. Each of these links consists of an inner rod 58a and an outer sleeve part 58b, which interfit telescopically as shown in Figure 7.

Rod 58a is shown provided with a flattened portion 61 to accommodate a leaf spring 60. This leaf spring can be attached to rod 58a to frictionally engage the inner wall of sleeve 58b, and serves to provide a small amount of friction between the parts and to avoid rattling.

Mounted upon each link part 58a, by pivotal connection 62, there is a latch finger 63. A part of this finger is formed by the adjustable stud 64, which has a rounded and generally conical shaped head 66.

In order to limit movement of the latch finger in one direction it is provided with an arm 67 carrying an adjustable stop screw 68. The end 15 of this screw engages an adjacent portion of the rod 58a, thus limiting rotation of the latch in one direction. Each latch finger is also provided with a spring 69 or like means tending to rotate the same in a direction to bring the screw 68 into contact with the adjacent rod 58a. In other words as viewed in Figure 5 the left hand latch finger 63 is urged in a clockwise direction, and the right hand latch finger is urged in a counter-clockwise direction.

25 The doors 16 are provided with latch plates 71 positioned to engage the heads 66 and to latch behind the same when the doors are swung to full closed position. Figure 4 illustrates the latch fingers locked with respect to the latch plates 71. 30 When the motor 13 is started in operation and the centrifugal device 28 starts to move the collar 36 toward the doors 16, the extensible links 58 are initially swung about the pivotal connection 59 to thereby swing the latch fingers 63 free of the latch plates 71. This initial movement of 35 the extensible link 58 is accommodated by lost motion in the links 47, whereby all of the effective force of the centrifugal device is initially applied for the unlatching action. Thereafter further movement of the collar 36 swings the doors to full open positions as previously described. When the doors snap back to full closed position 40 latch plates 71 slide over and past the conical shaped heads 66, to finally latch in full closed 45 position in the manner illustrated in Figure 4. Thus when the ventilator is not in use the doors are locked closed, unauthorized tampering from the exterior is prevented, and the passage through the ventilator housing is sealed with respect to the interior.

50 It will be evident from the foregoing that I provide simple and effective mechanism enabling opening and closing of the doors automatically, and also to effectively and positively lock the doors in closed position. The mechanism employed for this purpose, including particularly the centrifugal device 28, will operate for either direction of rotation, and therefore the ventilator can be used for moving the air in either direction. 55 If desired the motor can be provided with a suitable reversing switch for this purpose. The centrifugal device 28 described above is relatively simple in construction, and can be readily accommodated for different sized fans and ventilators. The quick opening and closing action of the doors 16 insures full opening action for normal operation of the ventilator, and also insures proper locking with the latch fingers 63. In addition the doors and their operating mechanism is such that the operation of the same does not detract from the efficiency of operation of the fan.

I claim:

1. In a ventilator, a housing adapted to be inserted in a wall, a rotatable shaft carried by the housing, a motor serving to drive the shaft, an

air moving fan mounted upon the shaft for moving air through the housing, closure doors pivotally carried by the housing and movable between open and closed positions with respect to the passage through the housing, spring means connected to move the doors toward either closed or open positions from an intermediate dead center position, centrifugal operating means carried by the shaft, and means connecting the centrifugal operating means to the doors to force said doors past said dead center position to cause automatic opening of the doors responsive to rotation of the shaft and to force the doors past said dead center position to close the doors responsive to permitting the shaft to come to rest.

2. In a ventilator, a housing adapted to be inserted in a wall, a rotatable shaft carried by the housing, a motor serving to drive the shaft, an impeller mounted upon the shaft for moving air through the housing, a pair of closure doors having adjacent edges of the same pivoted to the housing on axes extending generally diametrically across the housing, said doors being movable between limiting open and closed positions with respect to the passage through the housing, spring means connected to the doors to move the same toward either closed or open positions from an intermediate dead center position, centrifugal operating means carried by the shaft within the housing and adjacent one side of the closed doors, and means connecting said centrifugal means to said doors to force the same past said dead center position in a direction to open the doors when the shaft is rotated and to force said doors past said dead center position in a direction to close the same when the shaft is permitted to come to rest.

3. In a ventilator, a housing adapted to be inserted in a wall, a shaft carried by the housing, a motor connected to drive the shaft, a propeller mounted upon the shaft for moving air through the housing, closure doors pivotally carried by the housing and movable between open and closed positions with respect to the passage through the housing, centrifugal operating means carried by the shaft, latching means for latching said doors in closed position, means connecting the centrifugal operating means to the doors to open the same upon rotating the shaft and to close the same when the shaft is permitted to come to rest, and means actuated by said centrifugal operating means to release the latching means responsive to rotation of the shaft.

4. In a ventilator, a housing adapted to be inserted in a wall, a shaft disposed axially of the housing, an impeller mounted upon the shaft and serving to move air through the housing, a motor connected to drive the shaft, a pair of

closure doors pivotally carried by the housing and movable between open and closed positions with respect to the passage through the housing, centrifugal operating means carried by the shaft, latching means for locking the doors in closed position, and connecting the centrifugal operating means to the doors, said last means serving to operate the doors between open and closed positions, and means actuated by said centrifugal operating means to automatically release said latching means.

5. A ventilator as in claim 4 in which said latching means includes latch fingers adapted to engage latch plates on the doors.

15 6. A ventilator as in claim 4 in which said last means for connecting the centrifugal operating means to the doors includes a lost motion connection, and in which the connection between the latching means and the centrifugal operating means releases the latching means prior to applying opening movement to the doors.

20 7. In a ventilator, a housing adapted to be inserted in a wall, a shaft disposed axially of the housing, an impeller mounted upon the shaft serving to move air through the housing, a motor connected to drive the shaft, closure doors pivotally carried by the housing and movable between open and closed positions with respect to the passage through the housing, centrifugal operating means carried by the shaft, means connecting the centrifugal operating means to the doors to operate the doors between open and closed positions responsive to rotation and stoppage of the shaft, latching means for locking the doors in closed position, said latching means including latch devices movable between latch engaging and release positions, and means connecting said latch devices to said centrifugal operating means to move said latch devices between release and engaging positions responsive to rotation and stoppage of the shaft.
